US00D874326S

(12) **United States Design Patent** (10) Patent No.: **US D874,326 S**
(45) Date of Patent: **** Feb. 4, 2020**

(54) **GEMSTONE**

(71) Applicant: **BONOLI S.R.L.**, Forlì' (IT)

(72) Inventor: **Massimiliano Bonoli**, Forlimpopoli (IT)

(73) Assignee: **BONOLI S.R.L.**, Forlì (IT)

(**) Term: **15 Years**

(21) Appl. No.: **29/671,294**

(22) Filed: **Nov. 26, 2018**

CLAIM

I claim, the ornamental design for a gemstone, as shown and described.

DESCRIPTION

The file of this patent contains at least one photograph executed in color. Copies of this patent with color photograph(s) will be provided by the Office upon request and payment of the necessary fee.

FIG. 1 is a perspective view of a first embodiment of a gemstone, showing my new design;

FIG. 2 is a top view thereof;

FIG. 3 is a side view thereof, the remaining sides being a mirror image thereof;

FIG. 4 is a bottom view thereof;

FIG. 5 is a perspective view of a second embodiment of the gemstone, showing my new design;

FIG. 6 is a top view thereof;

FIG. 7 is a side view thereof, the remaining side views being a mirror image thereof;

FIG. 8 is a bottom view thereof;

FIG. 9 is a perspective view of a third embodiment of the gemstone, showing my new design;

FIG. 10 is a bottom view thereof;

FIG. 11 is a front side view thereof, the remaining side views being a mirror image thereof;

FIG. 12 is a top view thereof;

FIG. 13 is a perspective view of a fourth embodiment of the gemstone, showing my new design;

FIG. 14 is a front side view thereof, the remaining side views being a mirror image thereof;

FIG. 15 is a bottom view thereof; and,

FIG. 16 is a top view thereof.

1 Claim, 4 Drawing Sheets
